STETHOSCOPE

Filed Dec. 19, 1929

Fig. 2.

Theodore J. Case. Inventor

Stanley Lightfoot. Attorney

UNITED STATES PATENT OFFICE

THEODORE J. CASE, OF ANN ARBOR, MICHIGAN

STETHOSCOPE

Application filed December 19, 1929. Serial No. 415,222.

This invention relates to stethoscopes and has for its object to provide an improved means for audibly detecting very small vibrations such, for instance, as those set up by the muscles of the human body. A more specific object is to provide, in a stethoscope, an improved means of rendering audible vibrations of frequencies below 10,000 cycles per second, and more especially those below 10 200 per second.

It is an object of this invention to provide an improved amplifying reproducer by which small vibrations may be magnified to increase the intensity thereof and to utilize 15 this increased effect to vibrate an air column with sufficient magnitude as to render the vibrations clearly audible.

Another object is to provide a means for effectively isolating the reproducer in such 20 manner as to eliminate the disturbance of the air column or transmitter or other parts thereof by vibrations other than those it may be desired to listen to.

It is a further object of the invention to 25 provide an isolated reproducer as described which will be readily adjustable as to the desired pressures between the transmitter and a vibrating surface, or in another form so designed that the pressure on the surface to 30 be examined can be varied at will simply by altering the pressure of the hand holding the instrument.

It is likewise an object to provide a transmitter button which is variably adjustable 35 at will to increase or decrease the degree of magnification and in order to render it adaptable to different vibration frequencies. By such provision a very firm contact between the adjustable support and the supporting surface may be had while at the same 40 time allowing of a rather delicate adjustment as to the pressure on the transmitter button itself. In this connection it is a still 45 further and important subsidiary object to provide a transmitter button operatively connected to a diaphragm by means of a resilient floating support wherein the yielding pressure of the resilient support is exerted in such 50 manner as to maintain the diaphragm under

little or no tension in order to increase its sensitivity.

It is a further object to provide a means whereby the surface of contact with the area to be examined can be varied at will, and again, to provide a selective reproducer whereby the vibrations of low frequency will be transmitted to the diaphragm with little loss whereas the vibrations of higher frequencies will be relatively attenuated.

A still further object is to provide an improved device of the class described which will be very compact, very sturdy and inherently self protective due to the effective enclosure of the delicate parts.

Still further objects and advantages subsidiary or incidental to the aforesaid objects, or resulting from the construction or operation of the invention as it may be carried into effect, will become apparent as the said invention is hereinafter further disclosed.

In carrying the said invention into effect, I may provide a pick-up mechanism so designed and so arranged that waves of sound passing from a fleshy medium of relatively great density to a gaseous medium (air) of relatively less density shall suffer a minimum of loss and reflection in this transition, a loss much less than that which occurs when the air column of a stethoscope is set in vibration directly by the vibrations in the flesh undergoing examination.

Figure 1 represents a transverse vertical section taken centrally through my improved device; and

Figure 2 shows a side elevation of a modification of the device shown in Figure 1.

Referring more particularly to the drawings, the numeral 1 refers to a transmitter button suitably attached to a beam 2 hingedly connected to a ring 3 at one end and to an arm 4 at its other end. The arm 4 is pivotally mounted also on the ring 3 at one end and has its other end rigidly attached to a diaphragm 5 snared in the ring 3 by a smaller threaded ring 6. It will be noted that the connection between the beam 2 and the arm 4 is at a point closer to the hinged end of the arm 4 than to the diaphragm connection of this arm in order to provide a substantial leverage

for any movement of the transmitter 1 to the diaphragm 5. The hinge joining the beam 2 and the ring 3 is preferably resilient, as illustrated, maintaining the diaphragm 5 in a distended position until the pressure of contact on the button 1 shall overcome this resiliency and float the diaphragm in its most sensitive position.

The ring 3 is embedded at its periphery in a hollow member 7 which is made of some resilient material such, for example, as rubber and preferably shaped more or less as a toroid. Snared within the toroidal member 7 substantially above the diaphragm 5 is a solid disc 8 which completes an enclosed air chamber or sound box subject to the influence of the diaphragm. A hollow extension 8^a leads outwardly of the air chamber for attachment to the usual tubes and ear pieces (not shown). The toroidal member is externally attached as by embedding, to a rigid ring 9 threaded on its exterior surface to engage a mounting 10 which supports the toroidal member, diaphragm and transmitter. The mounting 10 extends downwardly as a protecting wall for the transmitter 1 and terminates in a resilient base ring 11. The ring 9 is adjustable with respect to the member 10 in order that the position of the transmitter may be altered to provide the desired pressure with a contacting surface to give the most favorable audition, and also to permit the withdrawal of the transmitter well up into the mounting 10 for protection when not in use.

According to the foregoing arrangement, it is obvious that vibrations from the hand of an operator or other external sources will not be transmitted to the diaphragm 5 as the diaphragm is very effectively isolated from all parts except the transmitter 1 even though a very firm pressure be applied to the top of the toroidal member.

It is preferred to make the transmitter 1 adjustable along the length of the beam 2 in order that sensitivity of the instrument to different vibration frequencies may be obtained, so that by adjusting the transmitter along the beam it may be set at the best point for effecting the reproduction of any desired vibration. Thus several examinations may be effected with the transmitter adjusted to several different points along the beam and certain vibrations thereby more or less isolated for the better determination of the actual conditions, as will be readily understood by those skilled in use of stethoscopes. In Figure 1 the beam is shown as being provided with a plurality of orifices 2^a in spaced relation along its length, into any one of which the stem of the transmitter 1 may be inserted.

It is further evident that transmitter buttons of any size may be readily employed, thereby making possible the examination of either small or large areas.

The instrument may be made selective in favor of the lower frequencies by properly proportioning the beam 4 so that it yields to the higher frequencies and does not pass them to the diaphragm whereas the lower frequencies are passed without attenuation.

In Figure 2 is shown a modification wherein in a transmitter button 12 is carried by a beam 13 attached through the medium of a spring arm to an inertia member 14 which is hingedly mounted at 15 to a support 16 which comprises a grip 17 and legs 18 preferably equipped with padded foot members 19. The inertia member 14 extends in both directions from its pivot 15, one end 20 forming an abutment for an adjustment screw 21 which is employed to determine the angular dip of the other end of the inertia member upon which is integrally mounted an amplifying reproducer 22 comprising an enclosed air chamber or sound box having a diaphragm 23 closing one end thereof and subject to vibrations from the transmitter button, the other end of the arm 13 being operatively attached to the center thereof.

Arising from the reproducer are suitable tubes 24 to which are attached the usual rubber tubes indicated in dotted lines 25 and which are intended to lead to the usual ear pieces (not shown).

The inertia member 14 is yieldably pressed toward the adjusting screw 21 by a spring 26 fixed to the support 16 and permits of an excellent control of pressure between the transmitter 12 and the surface which is to be examined while permitting of a very firm and non-interfering pressure from the legs 18 thereon. 13^a are orifices similar to 2^a of Figure 1 and for a like purpose.

If it be desired, a spring 27 or its equivalent may be employed to resist direct pressure on the button 12 and so prevent such pressure being transmitted to the diaphragm of the reproducer.

It will be apparent that numerous modifications may be made without departing from the spirit of my invention and I, therefore, desire to be limited in the application and construction thereof only by the scope of the appended claims.

What I claim is:

1. In a stethoscope, an amplifying reproducer, a resilient mounting for said reproducer, a transmitter, and a leverage connection between said transmitter and said reproducer.

2. In a stethoscope, a vibration amplifying means, a resilient mounting for said means, a transmitter button, a leverage connection between said transmitter button and said means, and a support for said resilient means extending downwardly about said transmitter.

3. In a stethoscope, a vibration amplifying means, a resilient mounting for said means,

a transmitter, a leverage connection between said transmitter and said means, and a support for said resilient means extending downwardly about said transmitter, said resilient means being adjustable as to height relative to said transmitter.

4. In a stethoscope, a vibration amplifying means, a resilient mounting for said means, a transmitter, a leverage connection between said transmitter and said means, and a support for said resilient means extending downwardly about said transmitter, said support having a resilient base for yieldingly contacting the surface to which the stethoscope may be applied.

5. In a stethoscope, an amplifying reproducer comprising an enclosed air column having a vibratory disc enclosing one end thereof, a resilient mounting for said reproducer, said mounting being adapted to absorb vibrations other than those transmitted directly to said disc, and a transmitter for contacting a vibrating member, said transmitter being operatively connected to said disc.

6. In a stethoscope, an amplifying reproducer comprising an enclosed air column having a vibratory disc enclosing one end thereof, a hingedly mounted transmitter operatively connected to said disc, said reproducer and said transmitter being carried by a vibration absorbing mounting, and a support for upholding said mounting and adapted to sustain said transmitter in operative position with respect to a vibrating surface.

7. In a stethoscope, an amplifying reproducer comprising an enclosed air column having a vibratory disc enclosing one end thereof, a hingedly mounted arm operatively connected to said disc, a hingedly mounted beam operatively connected to said arm, a transmitter carried by said beam intermediate the ends thereof and a support for said reproducer, said arm and said beam supporting said transmitter in operative relation with respect to a vibrating surface.

8. In a stethoscope, an amplifying reproducer comprising an enclosed air column having a vibratory disc enclosing one end thereof, a pivotally mounted arm operatively connected to said disc, a hingedly mounted beam operatively connected to said arm, a transmitter carried by said beam intermediate the ends thereof and a vibration dampening support for said reproducer, said arm and said beam, and a mounting for carrying said support and for maintaining said transmitter in operative relation with a vibrating surface.

9. In a stethoscope, an amplifying reproducer comprising an enclosed air column having a vibratory disc enclosing one end thereof, a hingedly mounted arm operatively connected to said disc, a hingedly mounted beam operatively connected to said arm, a transmitter carried by said beam intermediate the ends thereof and a vibration dampening support for said reproducer, said arm and said beam, and a mounting for carrying said support and for maintaining said transmitter in operative relation with a vibrating surface.

10. In a stethoscope, an amplifying reproducer comprising an enclosed air column having a vibratory disc enclosing one end thereof, a hingedly mounted transmitter operatively connected to said disc, said reproducer and said transmitter being carried by a vibration absorbing mounting, and a support for upholding said mounting and adapted to sustain said transmitter in operative position with respect to a vibrating surface, said mounting having a resilient base to directly contact said surface.

11. In a stethoscope, an amplifying reproducer comprising an enclosed air column having a vibratory disc enclosing one end thereof, a hingedly mounted arm operatively connected to said disc, a hingedly mounted beam operatively connected to said arm, a transmitter carried by said beam intermediate the ends thereof and a vibration dampening support for said reproducer, said arm and said beam, and a mounting for carrying said support and for maintaining said transmitter in operative relation with a vibrating surface, said mounting having a resilient base for directly contacting said surface, said mounting and said support being adjustably secured as to height to permit a pressure of variable magnitude between said surface and said transmitter.

12. In a stethoscope, a hollow resilient toroidal member, a rigid ring member embedded therein substantially concentric therewith, a diaphragm centrally mounted in said member, a rigid disc also centrally mounted in said member substantially above said ring, thereby forming an air chamber in said member, a transmitter, a leverage means hingedly attached to said ring and operatively attached to said diaphragm for supporting said transmitter, and means for supporting said toroidal member on a vibrating surface to accommodate said transmitter.

13. In a stethoscope, a hollow resilient toroidal member, a rigid ring member embedded therein substantially concentric therewith, a diaphragm centrally mounted in said member, a rigid disc also centrally mounted in said member substantially above said ring, thereby forming an air chamber in said member, a transmitter, an arm hingedly connected to said ring and operatively attached to said diaphragm, a beam also hingedly connected to said ring and operatively connected to said arm, a transmitter mounted on said beam intermediate the ends thereof, and supporting means for said member for maintaining

said transmitter in operative position with respect to a vibrating surface.

14. In a stethoscope, a hollow resilient toroidal member, a rigid ring member embedded therein substantially concentric therewith, a diaphragm centrally mounted in said member, a rigid disc also centrally mounted in said member substantially above said ring, thereby forming an air chamber in said member, a transmitter, an arm hingedly connected to said ring and operatively attached to said diaphragm, a beam also connected to said ring and operatively connected to said arm at a point closer to the hinge thereof than to the diaphragm center, a transmitter substantially beneath the center of said diaphragm, and supporting means for said member maintaining said transmitter in operative position with respect to a vibrating surface.

15. In a stethoscope, a hollow resilient toroidal member, a rigid ring member embedded therein substantially concentric therewith, a diaphragm centrally mounted in said member, a rigid disc also centrally mounted in said member substantially above said ring, thereby forming an air chamber in said member, a transmitter, an arm hingedly connected to said ring and operatively attached to said diaphragm, a beam also connected to said ring and hingedly connected to said arm at a point closer to the hinge thereof than to the diaphragm center, a transmitter substantially beneath the center of said diaphragm and a mounting adjustably secured to said member, said mounting having walls extending downwardly about said transmitter.

16. In a stethoscope, an enclosed air column having a vibratory diaphragm enclosing one end thereof, a beam supporting a transmitter button, said beam being operatively connected to said diaphragm at one end and spring supported at its other end whereby a floating support is provided therefor, and a support for said enclosed air column and said beam for maintaining said transmitter button in operative relation with a vibrating surface.

17. In a stethoscope, an enclosed air column having a vibratory diaphragm enclosing one end thereof, a beam supporting a transmitter button, said beam being operatively connected to said diaphragm at one end and spring supported at its other end whereby a floating support is provided therefor, said beam being depressed by said spring whereby said diaphragm is maintained distended, and a support for said enclosed air column and said beam for maintaining said transmitter button in operative relation with a vibrating surface.

18. In a stethoscope, an enclosed air column having a vibratory diaphragm enclosing one end thereof, a beam operatively connected to said diaphragm supporting a transmitter button, said button being receivable at a plurality

of points along the length of said beam whereby vibrations of different frequencies may be advantageously accommodated for transmission to said diaphragm, and a support for said enclosed air column, said beam being hingedly mounted on said support.

19. In a stethoscope, an enclosed air column having a vibratory diaphragm enclosing one end thereof, a beam having a transmitter button adjustably mounted thereon to different positions along the length of the beam to accommodate various vibration frequencies, a hinged arm operatively connected to the enclosure of said air column and to said diaphragm, said beam being hingedly connected to said arm and yieldably connected to said enclosure whereby said transmitter button is supported in a substantially floating mounting.

20. In a stethoscope, an enclosed air column having a vibratory diaphragm enclosing one end thereof, a beam having a transmitter button adjustably mounted thereon to different positions along the length of the beam to accommodate various vibration frequencies, a hinged arm operatively connected to the enclosure of said air column and to said diaphragm, said beam being hingedly connected to said arm and yieldably connected to said enclosure through the agency of a spring member positioned to depress said beam whereby said transmitter button is supported in a substantially floating mounting and whereby said diaphragm may be operated under little or no tension to increase its sensitivity.

21. In a stethoscope including a vibratory diaphragm, and a transmitter button operatively connected to said diaphragm, resilient means resisting body pressure on said diaphragm whereby, under conditions of use, said diaphragm shall be freely floating and under little or no tension.

22. In a stethoscope, a vibratory diaphragm, a transmitter button, a beam supporting said transmitter button, said beam being operatively connected to said diaphragm at one end and spring supported at its other end, said spring support being adapted to maintain said diaphragm in a free floating and substantially no tension condition when the transmitter button is operatively applied to an examined surface.

23. In a stethoscope, a vibratory diaphragm, a transmitter button, a beam supporting said transmitter button and operatively connected to said diaphragm, a handle operatively carrying said diaphragm and said beam, and yieldable means resisting the movement of said button in the direction of said diaphragm.

In testimony whereof I affix my signature.
THEODORE J. CASE.
